Attorney

UNITED STATES PATENT OFFICE.

CHARLES S. HANDELL, OF AURORA, ILLINOIS, ASSIGNOR TO RICHARDS-WILCOX MANUFACTURING COMPANY, OF AURORA, ILLINOIS, A CORPORATION OF ILLINOIS.

GARAGE-DOOR BOLT.

Application filed November 28, 1924. Serial No. 752,769.

My invention relates to bolts or fasteners designed particularly for large swinging or folding doors, such as are commonly used for garages, barns, and similar buildings, and has for its principal object to provide an improved fastener in the form of a double-acting bolt for securing both the top and bottom margins of the door, of such construction that it may readily be applied to doors of a variety of heights without alternation requiring the use of tools, and that both bolts may be simultaneously actuated in either direction by the operation of a single actuating device, such as a lever, the operating devices being such that they will function regardless of any adjustments for length that may have been made. Another object is to provide convenient means for locking the bolts against withdrawal. I accomplish these objects as hereinafter described and as illustrated in the accompanying drawings. What I regard as new is set forth in the claims.

In the drawings,—

Fig. 1 is a partial front elevation of the door opening and door of a garage or other building, the door being equipped with my improved fastener, which is shown in its operative or locking position;

Fig. 2 is a partial vertical cross-section on line 2—2 of Fig. 1;

Fig. 3 is a partial horizontal section on line 3—3 of Fig. 1;

Fig. 4 is a partial horizontal section on line 4—4 of Fig. 1;

Fig. 5 is a partial horizontal section on line 5—5 of Fig. 1; and

Fig. 6 is a perspective view of one of the clips by which the end portions of the fastener as an entirety are secured to the door.

Referring to the drawings,—7, 8 indicate, respectively, the top and bottom sills of a door opening, which, as shown, are provided with sockets or keepers 9, 10 to receive the upper and lower bolts proper, respectively, when projected. The door to which the fastener as an entirety is applied, which may be of any suitable description, is indicated by the reference numeral 11.

My improved fastener as an entirety comprises two bolts proper 13, 13, the construction of which is best shown in Fig.

2, each consisting of a tubular member or sleeve, the outer end of which is preferably bevelled, as shown at 14 in said figure, while the inner end thereof is reduced in diameter to provide a sleeve 15 which is square or otherwise made non-circular in cross-section, as best shown in Fig. 5. Each tubular member 13 is mounted to rotate and also to move longitudinally in a clip or half sleeve 16, the construction of which is best shown in Fig. 6, from which it will be seen that said clip consists of a semi-cylindrical portion 17 which embraces the tubular member 13 and is provided with laterally extending wings 18, 19 adapted to fit flatly against the face of a door and be secured thereto by screws 20. Said clip is provided with inwardly projecting curved lips 21 at opposite sides near its ends, which are concentric with the curvature of the cylindrical portion 17 and cooperate therewith to form a circular bearing for the tubular member 13, as best shown in Fig. 5. These lips hold the tubular member 13 from contact with the face of the door, and in cooperation with the cylindrical portion 17 of the clip hold it so that it easily slides longitudinally and may rotate freely. The cylindrical portion 17 of the clip 16 is also provided with an inclined or cam-shaped slot 22, and as illustrated in Fig. 1 the clips at the top and bottom of the door are reversed with relation to each other so that the slots 22 in said clips are oppositely inclined. Said clips, however, are identical in construction, so that any clip may be placed either at the top or at the bottom of the door. The two clips are axially alined so that the tubular members 13 at the top and bottom of the door are also in axial alinement. Each of said tubular members is provided with a radially-projecting pin 23 which projects into the slot 22 of the clip in which it is held, as shown in Fig. 1. It will be evident, therefore, that by simultaneously rotating the tubular members or bolts proper 13 in the same direction the engagement of their respective pins 23 with the slots 22 will cause said tubular members to be simultaneously projected or retracted, depending on the direction in which they are rotated.

The tubular members 13 are connected

so that they may be simultaneously rotated and moved endwise by means of a connecting rod 24, the upper and lower end portions 25, 26 of which are squared, or 5 otherwise made non-circular in cross-section to correspond with the cross-sectional contour of the sleeves 15, and they are of such dimensions that they have a telescopic or sliding fit with said sleeves, but non-rotatably engage them, as best shown in Fig. 2. In other words, the rod 24, through its end members 25, 26, is non-rotatably and extensibly connected with the tubular members 13. Thus it will be apparent that 10 the bolts proper are free to move endwise relatively to the operating rod as they rotate, and may be set closer together or farther apart to accommodate them to doors of different heights without affecting 15 the connection therewith of the operating rod 24, no tools or alterations being necessary to enable the fastener as an entirety to be applied to doors of different heights.

The connecting rod 24 is preferably made 20 in sections so that its length may easily be varied to suit different doors, and in the illustrated construction I have shown the several sections as being operatively connected together by providing them with 25 flattened end portions 27, 28, one of said flattened portions being provided with a pin 29 and the other with a hole adapted to receive said pin, as best shown in Fig. 2. The joint between the end portions of 30 connecting rod sections is enclosed by a clip 30 secured to the door and arranged to permit the connecting rod to rotate about its longitudinal axis. In assembling and mounting the fastener as an entirety, the 35 clips 30 are slipped upon one of the sections of the connecting rod, and after two sections have been connected it is moved up over the joint and then secured to the door.

The connecting rod 24 is rotated to actuate 40 the bolts proper by means of a lever 31 provided with a sleeve portion 32 that fits upon and is non-rotatably secured to said connecting rod. Said sleeve is held in position by means of a bracket 33 secured to the door and provided with ears 34, 35 at 45 opposite sides of the sleeve 32, as shown in Fig. 1. The lever 31 is hinged at 36 to the sleeve 32 so that it may swing vertically, as indicated by dotted lines in Fig. 1, and a staple 37, or equivalent device, is secured to the door in such position that when the lever 31 is swung to the position shown in dotted lines it may be secured to 50 said staple by a pad lock or other suitable means, thus preventing the actuation of said lever. It will be noted that when the bolts proper are projected the lever 31 is 55 parallel with the face of the door, and, therefore, when said lever is swung into

engagement with the staple 37 for locking purposes the bolts proper are in their projected or operative position; consequently locking the lever 31 to the staple locks the bolts and prevents their retraction. 70

From the foregoing description it will be seen that I have provided a fastener that may readily be applied to doors of various heights, and that the bolts proper may be simultaneously moved in either direction 75 by the actuation of a single lever. Furthermore, the construction described permits the operating lever to be mounted on the door at any desired height, as the connections between the said lever and the two 80 bolts need not be of uniform length, since a wide range of adjustability is provided for between the end portions of the connecting rod and the bolts proper, and, therefore, it is easy to obtain any desired length adjustment in connecting them.

What I claim as my invention and desire to secure by Letters Patent, is—

1. A fastener for doors comprising a rotatable bolt, a bearing member therefor adapted to be attached to the door, said bolt being mounted in said bearing member to rotate and simultaneously move longitudinally, and an operating device for the bolt mounted in a fixed position on the door and having an extensible connection with the bolt. 90

2. A fastener for doors comprising rotatable bolt, a bearing member therefor adapted to be attached to the door, said bolt being mounted in said bearing member to rotate and simultaneously move longitudinally, a rotatable operating device adapted 100 to be mounted in a fixed position on the door, and an extensible connection between 105 said operating device and said bolt.

3. A fastener for doors comprising a rotatable bolt, a bearing member therefor adapted to be attached to the door, said bolt being mounted in said bearing member to rotate and simultaneously move longitudinally, a rotatable operating device adapted 110 to be mounted on the door, and means connecting said operating device and the bolt comprising a coaxial member having telescopic, non-rotating engagement with the bolt. 115

4. A fastener for doors comprising a rotatable bolt, a bearing member therefor adapted to be attached to the door, an inclined slot and pin connection between said bolt and said bearing member whereby by rotating the bolt it may be projected or retracted, an operating device, and a connection between said operating device and the bolt extensibly connected with the bolt and disposed coaxially therewith. 120

5. A fastener for doors comprising a rotatable tubular bolt, a bearing member therefor adapted to be attached to the door, said 125

bearing member cooperating with the bolt to cause the same to move longitudinally when it is rotated, an operating device, and a rod connected with said operating device and having coaxial, non-rotating and telescopic engagement with the bolt.

6. A fastener for doors comprising a tubular bolt having a portion non-circular in cross-section, a clip securing said bolt to the door and forming a bearing in which the bolt may rotate and move longitudinally, an inclined slot in said clip, a pin carried by the bolt and operating in said slot, an operating device, and a connecting rod connected with said operating device and arranged to slide in the non-circular portion of the bolt.

7. A fastener for doors comprising a bolt, a semi-cylindrical clip for attaching the same to the door, said clip having inwardly-projecting lips arranged to cooperate with the semi-cylindrical portion thereof to form a bearing for the bolt in which it may rotate and move longitudinally, means actuated by the rotation of the bolt for moving it longitudinally, an operating device, and an extensible connection between the operating device and the bolt.

8. A fastener for doors comprising rotatable bolts adapted to be projected beyond opposite margins of the door, bearing members for supporting the bolts on the door to rotate and move longitudinally, a connecting

member telescopically connected coaxially with said bolts for simultaneously rotating them in the same direction, means actuated by the rotation of said bolts in the same direction to simultaneously move them in opposite directions longitudinally of said connecting member and an operating device for said connecting member.

9. A fastener for doors comprising bolts adapted to be projected beyond opposite margins of the door, bearing members for supporting the bolts and securing them to the door, a connecting member telescopically connected with said bolts for simultaneously rotating them in the same direction, and a lever for rotating said connecting member, adapted to be turned to lie parallel with the door when the bolts have been projected, said lever being hinged to swing relatively to said connecting member.

10. A fastener for doors comprising bolts adapted to be projected beyond opposite margins of the door, bearing members for supporting the bolts and securing them to the door, a connecting member telescopically connected with said bolts for simultaneously rotating them in the same direction, a lever for rotating said connecting member, arranged to lie parallel with the door when the bolts have been projected, and means carried by the door for holding said connecting member against endwise movement.

CHARLES S. HANDELL.
